MAIL SACK CART

Dominic L. Fiori, Denver, Colo.

Application March 28, 1952, Serial No. 19,097

Term of patent 14 years

(Cl. D14—3)

To all whom it may concern:

Be it known that I, Dominic L. Fiori, a citizen of the United States of America, residing at Denver, in the county of Denver and State of Colorado, have invented a new, original, and ornamental Design for a Mail Sack Cart, of which the following is a specification, reference being had to the accompanying drawing, forming a part hereof.

In the drawing:

Fig. 1 is a front view of a mail sack cart, showing my new design;

Fig. 2 is a side view thereof;

Fig. 3 is a top view thereof; and

Fig. 4 is a fragmentary, perspective view of the hanger portion of the said mail sack cart.

I claim:

The ornamental design for a mail sack cart, as shown.

DOMINIC L. FIORI.
